(57) **CLAIM**

The ornamental design for a textured fan housing, as shown and described.

DESCRIPTION

FIG. 1 is a perspective view of a textured fan housing showing my new design;

FIG. 2 is a side view thereof (views from the other side, top and bottom thereof are the same);

FIG. 3 is an enlarged plan view of a portion of the surface ornamentation of the textured surface of the fan housing shown in FIGS. 1 and 2; and,

FIG. 4 is a sectional view as taken along line 4—4 of FIG. 3.

The broken line showing of environmental structure in FIG. 1 is for illustrative purposes only and forms no part of the claimed design.
